UNITED STATES PATENT OFFICE.

GILES F. FILLEY, OF ST. LOUIS, MISSOURI.

COOKING-STOVE.

SPECIFICATION forming part of Letters Patent No. 235,347, dated December 14, 1880.

Application filed September 13, 1880. (Model.)

To all whom it may concern:

Be it known that I, GILES F. FILLEY, of St. Louis, Missouri, have made a new and useful Improvement in Cooking-Stoves, of which the following is a full, clear, and exact description, reference being had to the annexed drawings, making part of this specification, in which—

Figure 1 is a view, in perspective, of that part of the stove with which the improvement is immediately connected, the damper being turned up, and a portion of the outer and inner walls of the stove being broken away to exhibit the interior construction; and Fig. 2 a similar view, but the damper being turned down.

The same letters denote the same parts.

The present invention is an improvement in three-flue cooking-stoves, and it is one of a series of modifications of the construction patented to David H. Nation, June 1, 1880, and numbered 228,270.

In the construction referred to a division-strip is extended transversely from one side of the range to the opposite side thereof, just beyond the diving flues, and the heat-currents, in passing along the top flue, are drawn to the sides of the flue, and the heat is thereby applied to better advantage. This improvement has especial relation to the construction of the division-strip above mentioned and the arrangement of the damper.

Referring to the drawings, A represents the improved stove, having the fire-place B, the flue C leading from the fire-place, the diving flues D D, side bottom flues, E E, center bottom flue, F, ascending flue G, flue-space H, and oven I, all as in the construction referred to.

K represents the division-strip, extending from the side a of the stove to the side a', but mainly cut away at k k', immediately over the diving flues D D, leaving only a narrow portion, k' k', over the flues D D, and only for the purpose of providing shoulders for the two-wing damper M M' to strike against. The damper M M', in place of being arranged en-

tirely below the level of the oven-top, as in the former construction, is arranged partly below the oven-top i. The rear plates, d d, of the flues D D are extended upward higher than in the original construction shown in Nation's patent, but are not extended as high as the oven-top, and the damper M M' extends from the tops of the plates d d upward sufficiently to close the entire opening beneath the parts k' k', and as shown.

To heat the oven the damper is turned up, as shown in Fig. 1, and the heat-currents are then directed as indicated by the arrows in that figure. For direct draft the damper is turned down, as in Fig. 2, and the heat-currents then pass partly through the openings k k in the strip K and partly through the tops of the flues D D. The exit is at N, at the rear end of the stove.

The flue G is raised and constructed at its upper end as shown at g, giving a larger opening into the space H.

In the drawings, the strip K is shown cut away over the flues D D somewhat more than in the model. Either form, however, can be used without departing from the principle of the improvement.

I claim—

1. In a stove, A, the combination of the flues C, D D, and H, said flues C and H being separated by the strip K, and said strip being extended and cut away at k k', as described, and the flue H, having the escape N arranged at the end of the stove, substantially as set forth.

2. The combination, in a stove, A, of the flues C, D D, E E, F, G, and H, and damper M M', said flues C and H being separated by the strip K, and said strip being arranged, extended, and cut away at k k', as described, and the flue H having the escape N arranged at the end of the stove, substantially as set forth.

GILES F. FILLEY.
